UNITED STATES PATENT OFFICE.

JOHN MAGNUS, OF POPLAR BLUFF, MISSOURI, ASSIGNOR, BY MESNE ASSIGNMENTS, TO THE DALTON ADDING MACHINE COMPANY, OF CINCINNATI, OHIO, A CORPORATION OF OHIO.

ADDING AND RECORDING MACHINE.

1,134,958.

Specification of Letters Patent. Patented Apr. 6, 1915.

Application filed October 20, 1909, Serial No. 523,630. Renewed November 13, 1913. Serial No. 800,882.

To all whom it may concern:

Be it known that I, JOHN MAGNUS, a citizen of the United States, residing at Poplar Bluff, Missouri; have invented a new and 5 useful Adding and Recording Machine, of which the following is a specification.

This invention relates to adding and recording machines, and it has for its object to provide means operable by the keys to prevent 10 operation of the driving mechanism except when the keys have resumed their idle or normal position after operation thereof.

Another object is to provide, in combination with the operating mechanism and the 15 keys of an adding machine, locking devices under control of the keys adjustable to prevent operation of the driving mechanism at any time during operation of the keys, and to hold the driving mechanism in its idle 20 position so long as the keys are out of their normal or rest positions.

Another object is to provide, in combination with the special keys of an adding and recording machine such as a totals recording 25 key and the repeat key, locking devices for holding said special keys in operative adjustments, and a correction key having connections whereby said special keys may be restored to their idle positions at any desired 30 time.

Another object is to provide an adding and recording machine having a totals recording key and mechanism operable to record the totals contained in the machine 35 when said totals recording key is in operative adjustment, in combination with a latch or locking device for holding said totals recording key in its operative position, and means for releasing said latch or locking device from said key without operating the 40 machine to record the total.

There are other objects and advantages to be attained by the present invention, all of which will appear from the following description, reference being made to the drawings, in which—

Figure 1 is a side elevation of an adding and recording machine partially in section illustrating the device for releasing the 50 totals recording key and the repeat key from their operative adjustments. Fig. 2 is a sectional view of a part of the keyboard of a

machine showing the key-controlled devices for restoring the special keys to their idle positions without operating the machine. 55 Fig. 2 is a perspective view of the connections whereby the special keys are released by operation of the correction key. Fig. 3 is a detail view of the key-controlled locking mechanism whereby the driving mechanism 60 is locked against operation during operation of the keys. Fig. 4 is a sectional view of the key-levers showing the locking bar which rides thereon. Fig. 5 is a view illustrating the arrangement of the locking device with 65 respect to the driving mechanism. Fig. 6 is an inner side elevation of the same mechanism. Fig. 7 is a perspective view of the lock releasing device. Fig. 8 is a perspective view of the member which requires full 70 return of the operating mechanism to idle position after each operation.

The machine, in combination with which I have illustrated the present invention, is of well known type, including a main shaft 75 1 which is sometimes called the "driving shaft" since it controls the mechanism whereby the adding and recording devices of the machine are caused to operate. Said shaft is actuated in one direction and restrained in its idle position by suitable springs 2 connected to arms upon the shaft and to some other part of the machine. The shaft may be operated in the opposite direction by any mechanism adapted for such 80 purposes, and for convenience of illustration I have shown a handle 3 connected to one end of the shaft and constituting means whereby said shaft and the mechanism controlled thereby may be manually operated. 90 A set of keys 4 are embodied in these machines, said keys having levers 5 which project rearwardly into the machine and are operable to set up numbers in the movable carriage 6 of well known construction and 95 operation. As is well understood, the operating or "driving shaft" 1 and the mechanism controlled thereby, are put in operation to dispose of the numbers set up in the carriage 6 by adding and recording them. This 100 machine includes also a repeat key 7, by operation of which the carriage may be prevented from being returned after the number therein has been recorded or added,

thereby permitting said number to be repeatedly added and recorded by successive operations of the driving mechanism and the adding and recording mechanisms controlled thereby. As shown, said key 7 has a stem extending through a slot in the keyboard plate 8, and is provided with a notch 9 adapted for engagement with said plate when said key is in its depressed position. In this way the key may be locked in operative position and the number contained or represented in the carriage may be recorded and added as frequently as desired. This machine is also provided with a totals recording key 10 for well understood purposes, said key being also arranged in the keyboard and having a stem operating through a slot in the keyboard plate. Upon the stem of the totals recording key is a projection 11. A pawl 12 pivoted to the base of the machine is arranged to engage with the projection 11 when the totals recording key is depressed thereby to hold said key in said position. The pawl 12 has a spring 13 connected thereto whereby said pawl will be actuated into engagement with the projection 11 aforesaid. The machine of the type in which my invention has been embodied also includes an error or correction key 14 the stem of which operates through a slot in the keyboard and through a hole in the base of the machine, and rests upon an arm 15 attached to the rock shaft 16 supported in bearings below the base of the machine. Said shaft 16 has an arm connected to a link 17, and the rear end of said link is connected to the lever 18 operable to restore the carriage 6 to its idle position at the right after any number has been set up therein and without recording or adding said number. These devices constitute the ordinary error correcting mechanism as used in these machines as at present on the market.

My invention includes devices operable by the key 14 to release the repeat key and the totals recording key from their operative positions at any time without operating the recording or adding mechanism. The normal or idle position of the key 14 as shown in Fig. 2 is that in which said key is in its highest adjustment. Upon the stem of said key is a projection 19 adapted to engage when depressed with the arm 20 attached to the rock shaft 21 extending across the keyboard in front of the stems of the keys of the repeat and totals recording keys. A lever 22 attached to the rock shaft 21 has a link 23 pivoted thereto, the opposite end of said link having pin-and-slot connection 24 with the pawl 12 whereby said pawl may be operated by depression of the totals recording key independently of any movement of the said link 23. These connections, however, are arranged so that when the shaft 21 is rocked by depression of the correction key, the link 23 will move the pawl 12 to disengage same from the projection 11 and thereby permit the totals recording key to return to its idle position without previous operation of the driving mechanism. A depending arm 25 on the shaft 21 is connected to a link 26 which extends behind a pin 27 on the repeat key and operates when the shaft 21 is rocked as aforesaid to move the repeat key a distance sufficient to release the same from engagement with the keyboard plate, and thereby permit said key to return to its idle position. By use of these connections the usual error correcting key is utilized to restore the special keys to their idle positions as well as to eliminate or dissipate any number from the carriage that may have been set up therein.

A bar 28 extends transversely across the key levers 5, being retained in proper position thereon by pivoted arms 29 and actuated downwardly by a spring 30 extending from said bar to the base of the machine. To one end of the bar 28 a pawl 31 is pivoted, said pawl having a notch in one end which receives a stationary member 32 whereby said pawl will be operated on its pivot when the bar 28 is raised and lowered. A latch pawl 33 pivoted to the frame of the machine has a pin 34 on its lower end projecting under the pawl 31, said pawl 33 being actuated forwardly by a spring 35. A segmental plate 36 is attached to the shaft 1 and by engagement against an abutment 37 limits backward movement of the shaft and the parts operated thereby opposing the tension of the springs 2. A plate 38 is attached to one side of the segment 36 and is provided in its peripheral edge with a series of notches 39. When any one of the keys 4 is operated the bar 28 will be raised to disengage the pawl 31 from the pin 34. The spring 35 thereupon engages the lower end of the pawl 33 with one of the notches in the plate 38, thereby locking the driving mechanism against operation until the operated key has returned to its idle position permitting the bar 28 to be drawn downwardly by its spring 30 and the pawl 31 to engage with the projection 34 and thereby move the pawl 33 away from the plate 38. The error-correcting key is also operable to lock the driving mechanism against operation when said key is out of its normal or idle position. A link 40 (Fig. 2) is pivotally supported adjacent to the stem of the key 14 and has a cam surface against which the pin 19 on said key stem operates, thereby swinging the link 40 forwardly when said key is depressed. A link 41 connects said link 40 with a lever 42 (Fig. 6) which has an arm extending under the projection 43 on the bar 28, and it operates when the

correction key is depressed to raise the bar 28 with like effect as described in connection with the operation of the keys 4.

After the driving mechanism starts in operation, it is necessary for the full forward stroke thereof to be completed before said mechanism can be returned. The forward full stroke device includes a pawl 44 extending forwardly and arranged to ride upon the peripheral surface of the plate 45 attached to the segmental plate 36. Said plate 45 has notches 46 in its peripheral edge with which the pawl 44 will be engaged the moment the operating mechanism moves 15 from its normal position. This will prevent return of the operating mechanism until said pawl be disengaged from the plate 45 to permit the return of the parts. This disengagement is effected by the return full 20 stroke pawl 47 pivotally supported above the edge of the plate 36, and having a spring 48 whereby it is held in proper adjustment. When the operating mechanism is moving 25 on its forward stroke, the periphery of the plate 36 operates under the pawl 47 and raises said pawl. At the end of the forward stroke of the operating mechanism the plate 36 passes beyond the end of the pawl 47 and its parts are then adjusted for the return stroke. The plate 36 again moves under the 30 lower end of the pawl 47. Notches 49 in the peripheral edge of the plate 36 constitute means for engagement with the pawl 47 so that the driving mechanism must complete its full return stroke before said pawl 47 becomes disengaged therefrom. The pawl 47 has a forwardly extended rounded portion 50 (Fig. 8) which is arranged to engage with the pin 51 on the pawl 44 when 40 the said pawl 47 is operated by the return of the parts. This will raise and hold the pawl 44 out of engagement with the plate 45 until the return stroke has been completed, at which time the pawl 47 becomes 45 disengaged from the plate 36 and all parts resume their idle positions. The pawl 44 may be gravity actuated, but I prefer to use a spring 52 in connection therewith whereby said pawl will be yieldingly held in engagement with the mechanism described.

A stop bar 53 is pivoted to the frame of the machine and is upheld by a pin 54 extending over the lever 55. The lever 55 is supported by a projection 56 resting in the 55 notch on a pivoted support 57, the latter being upheld by a spring. At the forward stroke of the driving mechanism a projection 58 on the segmental plate 36 engages an arm of the support 57 and releases the 60 same from the projection 56 and permits the bar 53 to drop, this causes the point 59 of the bar 53 to engage in the notches 39 in the plate 38 and prevent further movement of the mechanism. This is timed to occur

only when the mechanism has moved the desired distance and after the plate 36 has passed beyond the lower end of the pawl 47. When said pawl 47 is raised the shoulder 60 thereon engages a pin 61 on the bar 53 and thereby raises said bar out of engagement with the plate 38. A projection 62 on the plate 36 engages the lower edge of the support 55 and raises said support to engage the projection 56 thereon with the supporting member 37 as previously described. 75 The entire driving mechanism is then in its idle position and is ready for another operation.

While I have shown and described the subject-matter of this invention embodied in a machine of the cross carriage type, it is perfectly obvious that it may be utilized in machines of nearly every known construction. I do not restrict myself to any specific embodiment nor to specific details 85 of construction and arrangement, but

What I claim and desire to secure by Letters Patent is—

1. In an adding machine, a movable carriage, means for setting up numbers in said carriage, mechanism for recording the numbers set up in said carriage and for moving said carriage in one direction, connections adjustable to prevent movement of said carriage, means for latching said connections 90 in position to prevent movement of said carriage, and separate means for releasing said connections, substantially as specified.

2. In an adding machine, a movable carriage, means for setting up numbers in said carriage, means for recording said numbers and moving said carriage to its idle position, connections adjustable to prevent movement of said carriage when said recording mechanism is operated, means for latching said 100 connections in position to prevent movement of said carriage when numbers are recorded, a lever, and means for operating said lever to release said connections, substantially as specified.

3. In an adding machine, a movable carriage, means for setting up numbers in said carriage and for moving said carriage, mechanism for adding the numbers set up in said carriage, means for operating said adding mechanism, means for restoring said carriage to idle position when said adding mechanism is operated, connections for preventing said carriage from being returned to idle position, means for latching said 115 connections in position to prevent movement of said carriage, a key controlling said adding mechanism for clearing operations, and means controlled by said key for releasing said connections, substantially as specified. 120

4. In an adding machine, a movable carriage, pins in said carriage, means for adjusting said pins to represent numbers,

means for moving said carriage during the setting of numbers, connections operable to restore said carriage to idle position, means for restoring said pins to idle position when said carriage is restored to its idle position, a repeat key co-operating with said carriage to prevent return of said carriage to idle position, means whereby said repeat key may be latched in operative position, and 10 separate means operable to restore said carriage and said pins to idle position and to release said repeat key from said latching means, substantially as specified.

5. In an adding machine, the combination with a movable carriage, means for setting up numbers in said carriage and for moving said carriage, and mechanism for setting up numbers and restoring said carriage to idle position at each adding operation, of mechanism for recording the totals representing said adding mechanism, a key for holding said adding mechanism to said recording mechanism in co-operative relation, means for latching said key in operative adjustment, connections for restoring said carriage to idle position independently of adding operations, and means controlled by said connections for releasing said key, substantially as specified.

30 6. In an adding machine, a movable carriage, means for setting up numbers in said carriage and for moving said carriage, mechanism for recording the numbers set up in said carriage, means for restoring said carriage to idle position when said recording mechanism is operated, repeat devices for preventing said carriage from being returned to idle position, means for latching said repeat devices in position to prevent movement of said carriage, adding mechanism controlled by said recording mechanism to add the numbers recorded, a key whose operation is necessary to enable said recording mechanism to record the total represented in said adding mechanism, and means controlled by said key for releasing said repeat devices, substantially as specified.

7. In an adding machine, a movable carriage, means for setting up numbers in said carriage and for moving said carriage, mechanism for recording the numbers set up in said carriage, means for operating said recording mechanism, adding mechanism controlled by said recording mechanism, means for restoring said carriage to idle position when said recording mechanism is operated, appliances for causing said carriage to remain in the position to which it is moved when said numbers are set up during repeated operations of said recording and adding mechanism, means for latching said appliances in adjustment to prevent movement of said carriage, a key

controlling said adding mechanism for clearing operations, means controlled by said key for releasing said appliances, and means for latching said key in operative adjustment, substantially as specified.

8. In an adding machine, a movable carriage, means for setting up numbers in said carriage and for moving said carriage, mechanism for recording the numbers set up in said carriage, means for operating said recording mechanism, adding mechanism controlled by said recording mechanism, means for restoring said carriage to idle position when said recording mechanism is operated, appliances for causing said carriage to remain in the position to which it is moved when said numbers are set up during repeated operations of said recording and adding mechanisms, means for latching said appliances in adjustment to prevent movement of said carriage, a key controlling said adding mechanism for clearing operations, means controlled by said key for releasing said appliances, means for latching said key in operative adjustment, and means for releasing said key, substantially as specified.

9. In an adding machine, a movable carriage, means for moving said carriage to different selected positions from a definite starting position, a rock shaft, means operated by said rock shaft for moving said carriage to its starting position, a device adjustable to prevent movement of said carriage by said rock shaft, means for holding said device in position to prevent movement of said carriage in successive operations of said rock shaft, manually operable means for moving said carriage to its starting position independently of said carriage, and elements operated by said manually operable means for releasing said device, substantially as described.

10. In an adding machine, the combination with a depressible key controlling the recording of totals in its depressed position, of a pivoted element arranged to engage and hold said key in its depressed position, a rock shaft, means for rocking said shaft, a lever attached to said shaft, a link connecting said lever with said pivoted element whereby said element is released from said key by the rocking of said shaft, and means permitting said key and said pivoted element to be engaged with each other independently of any movement by said shaft, substantially as described.

11. In an adding machine, the combination with a carriage movable to different selected positions from a definite starting position, of a rock shaft operable to move said carriage to its starting position, a device adjustable to prevent movement of said carriage when said rock shaft operates, a manu-
